UNITED STATES PATENT OFFICE**160,035****TRUCK****Frank G. Tilley, Jacksonville, Tex.****Application December 29, 1948, Serial No. 150,430****Term of patent 14 years****(Cl. D14—3)*****To all whom it may concern:***

Be it known that I, Frank G. Tilley, a citizen of the United States, residing at Jacksonville, Texas, have invented a new, original, and ornamental Design for a Truck, of which the following is a specification, reference being had to the accompanying drawings, forming part thereof.

Figure 1 is a side view of the truck with side standards lowered and cabinet doors closed;

Figure 2 is a rear view of the truck in the condition shown in Figure 1;

Figure 3 is a side view of the truck with doors to side cabinets opened;

Figure 4 is a top plan view of the truck with side doors closed.

The characteristic features of my design reside in the portions shown by means of full lines in the drawing.

I claim:

The ornamental design for a truck, as shown and described.
